UNITED STATES PATENT OFFICE.

JAMES W. SILVER, OF OGDEN, UTAH.

BEET DUMP.

Application filed January 18, 1926. Serial No. 82,031.

This invention relates to beet dump apparatus adapted for location at beet dump stations for handling wagon-loads of sugar beets that are hauled from the field and delivered, substantially free of refuse, ordinarily to railroad beet cars for transportation to the sugar factory.

At such stations, for reasons well understood, each loaded field wagon or truck is initially weighed before dumping its load into association with the beet dump apparatus of the station, which apparatus embodies or has associated therewith screening means, for separating the dirt, leaves or other refuse from the beets proper as delivered to the railroad beet car, the refuse being collected in a tare receptacle or chute for redelivery to the same aforesaid wagon for reweighing to determine the tare to be deducted, from the initially weighed load, and hence the actual weight of the beets to be accounted for.

Various types of beet dump apparatus have been employed to accomplish the foregoing general aims, and I am aware of the fact that some of such structures embody a main inclined endless conveyer discharging to an auxiliary endless screening conveyer, adapted to be conjointly disposed at sub-

stantially right angles to the railroad trackage, while others embody a main inclined conveyer discharging into a rotary cylindrical screen, adapted to be conjointly disposed substantially parallel of the railroad trackage, the screen delivering the refuse to a tare receptacle underneath the same, and the apparatus providing for means to discharge the beets from the outer end of said screen laterally towards said trackage.

In these forms of apparatus, however, although in one sense they may be termed a parallel type of station, they are not of the same parallel system of layout as will hereinafter be disclosed. As a matter of fact they so obstruct the space adjoining the railroad trackage as to make it impracticable to maintain a substantially straight team driveway approximately parallel to the railroad track between the receiving beet hopper and the tare receptacle, which arrangement broadly and specifically, according to my improvements, not only provides for substantial economy, from several aspects, but is also eminently desirable for teaming

or trucking purposes. The beet hopper of 55 such former apparatus is located on the off-side of the inclined conveyer, the conveying means proper being disposed between the hopper and the railroad trackage, and furthermore these hoppers are disposed as a 60 bodily whole substantially above the ground level, which necessitates the construction of a team driveway, embodying an elevated platform having reversely disposed ramps, as well as a hoisting framework for dumping 65 the heavily loaded beet wagons, all of which not only adds greatly to installation costs but also remains in the nature of a permanent structure, whereas the remaining apparatus is now generally constructed as 70 portable units, so that if that particular dump station is to be abandoned for another location, or is to remain idle for any other reasons, it becomes necessary to separately build up another hopper, elevated 75 wagon driveway and hoisting framework, at each location where the portable units of the apparatus are to be used.

One of the primary objects of my improvements, therefore, has been to devise 80 such a parallel layout type of beet dump station that the team driveway on the regular railroad right-of-way will not be impaired or obstructed by the installation of the station, and will serve also as the station driveway 85 between the inclined conveyer and the railroad track, or along the nearside of the main conveyer and the receiving beet hopper, relatively to the railroad trackage, it being particularly noted that said hopper extends in longitudinal line with and has its discharge outlet disposed in the plane of 90 said main conveyer, and which driveway will preferably lie in a level and approximately straight path from the said hopper 95 to the tare receptacle.

Further primary objects of the invention reside in the improved structural features of the apparatus itself and the novel combination and arrangement of the elements thereof, including the novel form and disposition of the beet hopper with an initial feeder conveyer associated therewith, for delivering the beets with a more regulable and freely discharging feed from the hopper to the inclined endless conveyer; the structural form of the gallows hoisting framework, associated with said hopper for dumping the

heavily loaded field wagons, which framework is of portable character or which may be readily knocked down for portability; and also including the novel arrangement of cross-conveyer units associated in combination with the discharge end of said main inclined conveyer.

The foregoing and other features, objects and advantages of the improvements, however, will be so clearly apparent it is believed, as incidental to the following disclosure, that no useful purpose would be served by further enlarging upon the same initially, and with these general outlining remarks, therefore, reference will now be immediately had to the accompanying drawings, illustrating a practical embodiment of the improvements, in which drawings:—

Figure 1 is a side elevational view of the improved beet dump apparatus shown at Figure 2, looking towards the nearside thereof relatively to the railroad trackage; Figure 1^a is a vertical transverse sectional view, through the receiving hopper and initial feeding conveyer, taken along the line *a*—*a* of Figures 1 and 2; Figure 2 is a plan view of the apparatus as associated with the railroad trackage, and showing the clearance space for the team driveway from the receiving hopper to the refuse or tare receptacle; Figure 3 is an end elevational view of the discharge end of the apparatus, and also showing in dotted lines a railroad transportation beet car, positioned for the reception of the screened beets, as well as one of the field wagons or trucks in position, under the tare receptacle, for receiving the refuse material from its previously dumped load of beets; Figure 4 is an enlarged fragmentary view, analogous to Figure 3, partly in elevation and partly in longitudinal vertical section through the screening cross-conveyer and the tare receptacle; and Figure 5 is an end elevational view at the receiving hopper end of the apparatus, being a vertical transverse section along the line *b*—*b* of Figure 2, and also showing in dotted outline one of the field wagons or trucks as located at its dumping position.

It may be well to initially state, for a clearer conception of the general layout of the apparatus, that in carrying out my invention I preferably provide a main inclined conveyer structure 6, adapted to be disposed in a plane substantially parallel to the railroad trackage 13, which main conveyer at its upper end is associated with a laterally disposed or cross-conveyer 7 that is in turn associated with a terminal cross-conveyer 8, in the form of a screening unit, adapted to discharge at substantially right angles over a transportation car 14 on the railroad track, a substantially elevated tare receptacle 9 being located directly underneath the inner end of said screening conveyer; while at the

lower end of the main conveyer an initial feeder conveyer structure 10 is provided, for discharging at its forward end over upon the main inclined conveyer, and longitudinally extends at its rear end directly underneath a beet load receiving hopper 11, so located and constructed as to receive the dumped loads of beets, from the field wagons or trucks 12, at a position on the nearside of the apparatus relatively to the railroad trackage, and it being particularly noted that the said main inclined conveyer, the said beet load receiving hopper with its discharge outlet, and the interposed said initial feeder conveyer are all disposed in endwise alignment with each other, or extend in the same longitudinal plane which in the layout as illustrated, and preferred, is a vertical plane parallel to the railroad trackage. Accordingly, the whole arrangement provides for a wholly unobstructed clearance space 15, along the railroad right of way between the trackage and the apparatus, whereby the field wagons or trucks 12 are hauled over a substantially straight driveway 16, as indicated by the long arrow of Figure 2, from the beet hopper 11 to a position under the tare receptacle 9.

All of the conveyers are of the endless type and, in so far as my present improvements are concerned, may be of any suitable form in detail, but I prefer that the conveyers 6, 7 and 10 be of roller supported endless belt structure, as distinguished from an endless series of pan, bucket or like conveyers which tend to bruise the beets. Also, as a matter of preferred structure and in order to avoid a more prolix description, although it may be necessary in some instances later on to go more into detail, I have illustrated the main conveyer 6 and the terminal screening conveyer 8 substantially of the same forms, although disposed differently in assembly, as shown in United States Patent No. 1,432,195 granted October 17, 1922 to James A. Lynch, and the intermediate cross-conveyer 7 may be of substantially the same structure as the main conveyer, while the feeder conveyer 10 is illustrated as being substantially the same as that disclosed in my prior application, for endless belt conveyers, filed October 6, 1925 under Serial No. 60,823.

A suitable equipped upstanding framework or tower 17, preferably built of structural steel, supports the belt cross conveyer 7, which may be conveniently termed an auxiliary or interposed cross-conveyer, the terminal screening cross-conveyer 8, the tare receptacle 9 which has an open bottom closed by a counterbalanceingly weighted or self-closing and latching door 19, and the upper end of the main inclined conveyer 6; but the lower end of the main conveyer 6 preferably extends in proximity to the ground level, and may be projected into a concrete

walled pit 20 within which is located the rear horizontally disposed section 21 of the feeder conveyer 10 that has a forward upwardly inclined section 22 discharging longitudinally over and upon the lower end of the main conveyer 6.

The numeral 23 designates the operator's platform, 24 a walkway extending alongside the main and cross-conveyers, to provide for inspection of the apparatus, 25 and 26 hoist and clutch operating connections or rods, each controlled by its respective lever 27, and 28 designates a hoisting cable, herein-after referred to in connection with a wagon 15 dumping gallows frame, for tilting the field wagons to dump their load of beets into the feeder hopper.

The numeral 29 indicates a drive wheel or pulley arrangement, operated from a 20 motor house or suitable power station indicated by the motor 30, which driving mechanism through interposed gearing, indicated generally by the numeral 31 in Figures 1 and 2, drives a clutch controlled drum, for 25 the hoisting cable 28, as well as the head roller for the main belt conveyer 6, and the tail roller of said conveyer 6 may be suitably geared up with the head roller of the feeder conveyer 10 for driving the latter. Analogously, as indicated generally by the numeral 30 32 in Figures 2, 3 and 4, suitable chain and sprocket gearing is interposed between the main driving mechanism and the head roller shaft 33 of the auxiliary belt conveyer 7, 35 as well as between the said shaft 33 and the shaft 34 of a spider element or radial set of beater arms 35, which alternately engage the underneath upper portion of the terminal screening conveyer 8, embodying an endless 40 series of suitably spaced and formed springy cross-members or slats, for raising and lowering the same with a wave-like agitating motion to better sift the refuse therethrough, and finally between the said beater shaft 45 34 and the head sprocket shaft 36 of said screening conveyer, the rear sprockets 37 for the latter being simply idler guiding sprocket wheels, mounted at each side of the screening conveyer on independent stub 50 shafts 38, for the side sprocket chains of the conveyer to reeve over. As the same is so obvious and well understood, the aforesaid gearing connections are only shown more or less conventionally and described generally 55 for the sake of brevity.

Also, as in the Lynch patent aforesaid, it will be noted that an apron or bottom wall 39 extends, underneath the lower portion of the endless series of slats 40, from the 60 forward end of the screening conveyer 8 towards the rear thereof, for delivering the screened out refuse from the beets to the tare receptacle 9. Likewise, it will be further noted that the screening conveyer frame is 65 hingedly mounted, with its tail end over

the said tare receptacle and approximately underneath the discharge end of the cross-conveyer 7, if the latter be actually employed which appears to be desirable, although it is possible that the auxiliary cross-conveyer 70 75 could be dispensed with, in which latter event the screen conveyer would probably have to be made longer, and at any rate under such circumstances the tail end of the screening conveyer and the tare receptacle would then have to be located approximately underneath the discharge end of the main conveyer 6; but the employment of the auxiliary cross conveyer is desirable for many reasons. The hinged mounting of the screening conveyer 80 permits of a tilting and folding-up adjustment of the same, for obvious reasons, by means of a cable 41 operated by a worm gearing arrangement, indicated generally at 42, which may be actuated manually by a crank 85 handle applied to the worm shaft thereof. Outside of the novel broad arrangement of the cross-conveyers relatively to the main conveyer 6, however, no particular claim is made to the specific constructions thereof, 90 so that further detailed description of the same is not believed to be necessary nor desirable.

In now describing the more important features, perhaps, of my improvements in 95 combined arrangement with the lower end of the main conveyer 6, as has before been stated the feeder conveyer 10 is preferably mounted on the bottom of a pit 20, sunk below the driveway 16, with the inclined head section 21 of said feeder conveyer discharging longitudinally over and upon the lower end of the main inclined conveyer 6, which latter in turn is adapted to be disposed in a vertical plane parallel to the 100 railroad trackage.

Immediately above the horizontal tail section 21 of the feeder conveyer 10, and with its lower portion disposed within said pit, is mounted the beet load receiving hopper 11, 110 built up of steel bents preferably and wall boards, which hopper is of a novel construction, peculiarly adapted for the beet dump station, and extends as before stated in longitudinal line with both said feeder and main 115 conveyers.

It is to be particularly noted that the nearside wall 42 of this hopper, relatively to the driveway 16, is of substantially less height than the farside wall 43 thereof, 120 the two downwardly convergent said side walls so terminating at their lower edge portions as to provide for a longitudinally extending slot or bottom discharge opening, which preferably diverges forwardly, as indicated by the rearwardly tapering lower end portions 44. The rear of said hopper may be closed by a boarded wall 45, and the forward end partially closed by the boarded wall 46, excepting at the central zone thereof 125 130

where it is left unobstructed, as at 47, to provide a forward discharge opening for the hopper, in line with the bottom opening thereof, which forward opening is in open 5 unobstructed communication with a forward discharge throat that simply comprises a pair of upstanding side or flanking walls 48, preferably convergent slightly both 10 downwardly and forwardly, as seen more clearly from Figures 1 and 2.

It being understood that the bottom opening 44 of the hopper and the bottom opening 15 between the side walls 48, of the forward discharge guiding throat therefor, are disposed immediately over the horizontal and inclined portions, respectively, of the conveyer belt of the feeder 10, it will be apparent that the side walls of the feeder conveyer may be made quite shallow, and at 20 the same time provide for the proper feed of the beets therealong without tumbling over the sides. Also, owing to the tapered formation of said openings, the loads of beets from the field wagons, weighing several 25 tons each, are caused to be moved forwardly with a more regulable feed and discharged more freely than otherwise would be the case, especially because of the forward 30 end of the bottom opening 44 being wider than its rearwardly tapering portion.

It is further to be particularly noted that, 35 with this particular type and disposition of the beet load receiving hopper, it is not necessary to build up an elevated platform or wagon-way at the station to provide for the dumping of the heavily loaded contents of the field wagons into the hopper, because the lower or nearside wall 42 of the hopper is disposed adjacently of and projects only 40 a short distance above the team driveway level 16, as seen most clearly from Figures 2 and 5, which arrangement provides for a substantially level and straight driveway 45 for the teams, along the actual railroad right-of-way between the trackage and the apparatus, as thus located, from the beet hopper to the tare receptacle, whereby there is afforded such a clearance space or driveway that is wholly unobstructed by the apparatus as a whole, or any part thereof, 50 either with reference to beet hauling field wagons or any other type of vehicles ordinarily using the roadway, and without the necessity of having to haul the heavily loaded field wagons initially up an incline or ramp, for dumping their load of beets into the hopper as is now customarily done, which feature of itself is very important from a trucking viewpoint.

60 A wagon tilting gallows or hoisting framework surmounts the pit 20, in straddling or encompassing relation with the beet hopper, and may embody the open base frame structure 49 having an upstanding post beam 50 from which is projected the

hoisting beam 51, extending laterally over the driveway 16 in the zone of the hopper, this upper structure being suitably braced and trussed by the angularly disposed strut bars 52 and 53. The outer end of the hoisting beam 51 suspends a tackle block arrangement 54, associated with the aforementioned hoisting cable 28 that reeves respectively over and under the upper and lower guiding pulley wheels 55 and 56 carried by the base 75 frame structure.

This hoisting framework and also the tower framework 17 are preferably formed of structural steel which may be facilely assembled and also readily knocked down 80 for removal and reinstallation purposes, and as the hopper, the feeder conveyer, the main conveyer, the auxiliary conveyer, and the screening conveyer, together with the latter's tare receptacle, are built up as independent portable units, it is obvious that the whole station may readily be disassembled and transported as units, for reinstallation at another place or for storage during closed seasons, in avoidance of deterioration. Or as a matter of fact, which will also be obvious, the apparatus as a whole, or as attachable and detachable units, might readily be supported upon a wheeled base structure or separate structures, for self-portability as it were.

Although not actually shown in the drawings, it is to be understood that the belts of the main conveyer 6 and of the feeder conveyer 10 are provided on their outer or 100 conveying faces with laterally disposed cleat-like spaced abutments, preferably spring steel bars or slats mounted as disclosed in my aforesaid application, to properly convey the beets and refuse up the inclines, as well as to support the belts against undue sagging.

Finally it may be emphasized again that, 110 with the preferred arrangement which in its broader sense also involves a novel method of handling the beets at a beet dumping station, the heavily loaded field wagons are tilted, by the hoisting block and tackle means 54, to dump their loads into the receiving hopper from the ground level and over the shorter nearside of the hopper, relatively to the railroad trackage, without the necessity of being hauled up an inclined platform structure, the building of which latter would also involve considerable expense, and from that dumping position the emptied wagons are then hauled over a substantially level and straight driveway, along the railroad right-of-way between the trackage and the apparatus, to a position underneath the tare receptacle 9, for receiving the screened out dirt from the initially weighed load. In the meantime, the beets and refuse of any particular load are gradually fed to and along the feeder conveyer 10, as hereinbefore de- 120 125 130

scribed, discharging to the lower end of the main inclined conveyer 6, disposed in a vertical plane parallel to the trackage, from the upper end of which main conveyer they are again discharged to the inner end of the cross-conveyer 7, which is disposed substantially at right angles to the main conveyer, and from this auxiliary cross-conveyer 7 the beets and refuse are discharged to the screening conveyer 8 which is also disposed, in the vertical plane of the auxiliary conveyer, at substantially right angles to the main conveyer and railroad trackage, for finally discharging the screened beets into a transportation car, while the screened out refuse is fed down the apron 39 into the tare receptacle 9.

During this travel of the beets, along the several endless conveyer units, they have three distinct but slight tumbling over or cascading motions, once on discharging from the feeder to the main conveyer, again on discharging from the main to the auxiliary cross-conveyer, and finally upon discharging from the auxiliary to the screening conveyer. Each of these short falls imparts shocks tending to substantially dislodge the clinging dirt from the beets, without bruising the latter, so that in passing over the terminal screening conveyer the refuse is more completely sifted between the endless spaced series of bars thereof, being further aided by the wave-like agitation thereof caused by the intermittently impacting arms 35 of the rotating spider.

From all of the foregoing, it is believed that the full objects and advantages of the invention will be clearly apparent, but although I have thus set forth the invention in detail, in accordance with my present preferences, it will nevertheless be understood that I do not wish to unnecessarily confine myself to all of the details exactly as disclosed, excepting as they may come within the terms or tenor of the claims, or equivalent steps, elements, combinations and arrangement thereof, or as fairly interpreted in the light of the specification if necessary.

What I do claim, as new and patentable, is:

1. In beet dump apparatus, the combination of a main inclined conveyer, transverse conveyer means embodying screening means projected laterally of one side of said main conveyer at the upper end thereof for discharging the clean beets on that same side of the main conveyer, a substantially elevated tare receptacle mounted underneath said screening means for receiving and discharging the refuse from the beets also on the same side of said main conveyer as the discharge of the clean beets, a beet load receiving hopper disposed at the lower end of said main conveyer in the longitudinal line thereof, and wagon dumping means associ-

ated with said hopper and likewise located on the same side of the apparatus as are said screening means and tare receptacle.

2. In beet dump apparatus, the combination of a main inclined conveyer, transverse conveyer means embodying screening means projected laterally of one side of said main conveyer at the upper end thereof for discharging the clean beets on that same side of the main conveyer, a substantially elevated tare receptacle mounted underneath said screening means for receiving and discharging the refuse from the beets also on the same side of said main conveyer as the discharge of the clean beets, a beet load receiving hopper associated with the lower end of said main conveyer in the longitudinal line thereof, which hopper has a low side located on the same side of the apparatus as are said screening means and tare receptacle, and wagon dumping means associated with said low side of said hopper and likewise located on the aforesaid same side of the apparatus.

3. In beet dump apparatus, the combination of a main inclined conveyer, transverse conveyer means embodying screening means projected laterally of one side of said main conveyer at the upper end thereof for discharging the clean beets on that same side of the main conveyer, a substantially elevated tare receptacle mounted underneath said screening means for receiving and discharging the refuse from the beets also on the same side of said main conveyer as the discharge of the clean beets, an endless feeder conveyer disposed in longitudinal line with said main conveyer and discharging upon the lower end thereof, a beet load receiving hopper disposed over said feeder conveyer, in longitudinal line therewith and with said main conveyer, and wagon dumping means associated with said hopper and likewise located on the same side of the apparatus as are said screening means and tare receptacle.

4. In a beet dump station, the combination of a main inclined conveyer disposed in a vertical plane substantially parallel with the railroad trackage of the station, transverse conveyer means embodying screening means projected laterally of one side of said main conveyer at the upper end thereof, for discharging the clean beets on that same side of the main conveyer at a position over said trackage, a substantially elevated tare receptacle mounted underneath said screening means, for receiving and discharging the refuse from the beets at a position between the aforesaid same side of the main conveyer and said trackage, a beet load receiving hopper operatively associated with the lower end of said main conveyer in the longitudinal line thereof, and means likewise disposed on said same side of the apparatus,

as are said screening means and tare receptacle, for dumping beet loads into said hopper over the nearside thereof, relatively to the railroad trackage, from field wagons positioned on the ground level at that nearside and headed in approximately direct line towards the position of said elevated tare receptacle, whereby the railroad right-of-way

itself, between said main conveyer and trackage, provides for an unobstructed substantially straight and ground level driveway, for the field wagons, from said hopper to a position underneath said tare receptacle.

In testimony whereof I affix my signature.

JAMES W. SILVER.
